UNITED STATES PATENT OFFICE.

STEPHEN J. BRENNAN, OF HOLYOKE, MASSACHUSETTS.

STORE-SERVICE TROLLEY-TRACK.

SPECIFICATION forming part of Letters Patent No. 595,555, dated December 14, 1897.

Application filed December 10, 1896. Serial No. 615,212. (No model.)

To all whom it may concern:

Be it known that I, STEPHEN J. BRENNAN, a citizen of the United States of America, residing at Holyoke, in the county of Hampden 5 and State of Massachusetts, have invented new and useful Improvements in Store-Serv-ice Trolley-Tracks, of which the following is a specification.

This invention relates to store-service trolley-tracks, and particularly to such tracks made of wire or wire cables, the object of the invention being to provide a trolley-track for the support of the upper end of a ladder, such as is used in stores or warehouses for giving 10 convenient access to the upper shelves in such places, which track shall be cheap, of light construction, and noiseless; and the invention consists in the construction of a wire track, all as fully described in the following 15 specification and claim.

In the drawings forming part of this specification, Figure 1 is a perspective view of a track constructed according to my invention. Fig. 2 is a detail view of a part of one of the 20 anchor-brackets. Fig. 3 is a plan view from above, showing the position of a movable support intermediate of the two anchor-brackets at each end of the track and in dotted lines is shown another position of said support. Fig. 4 shows an anchor-bracket for a single-wire track. Fig. 4^a is a detail section of said 25 single-wire bracket. Fig. 5 is a view showing the construction of a trolley attached to the upper end of a ladder for use on said 30 wire.

In the drawings, A represents two parallel tracks made, preferably, of steel wire.

B is an anchor-bracket, to which the ends of the wire tracks A are attached. A bracket 40 is required for each end of the track to be established, and said brackets consist of a base 2, which may be bolted or screwed to the timbers of the ceiling whereon it is desired to locate said track. Depending from 45 said base and preferably integral therewith are two bracket-arms 3 3, on the lower ends of which are the hubs 4 4, having longitudinal passages 5 therethrough, in which are secured the ends of the wire tracks A. In Fig. 50 2 one of these hubs is shown in section somewhat enlarged, and one end of one of said tracks is shown in position therein. The

ends of said tracks may be threaded and secured in said hubs by a nut on said threaded portion, as shown in Fig. 4, if desired, but 55 the preferable manner of securing the ends of said tracks in said hubs is to pass the ends thereof through said hubs 4 and then make a short spiral turn in said ends, as shown in said Fig. 2, and then fill the said passage 5 60 with some metal, as lead, in a melted condition, which on cooling leaves the end of said track firmly embedded in said metal. Said bracket is preferably made of cast-iron and said base and bracket-arms all cast in one 65 piece. At the inner end of said base two lugs 6 6 are cast thereon, between which is pivoted the tightening-arm 7, having the cross-head 8 thereon, which is provided with grooves 9, with which the wires A engage. A toothed 70 rack 10 is cast on the base of the bracket, as shown, and a tightening-lever pivotally secured to said arm 7 by one end engages by its opposite end one of the notches of the said rack 10. Said tightening-lever is made in 75 two parts 14 and 15, which are united by a long sleeve or nut 16, provided with a right and left hand screw-thread in the ends thereof to receive the similarly-threaded ends of the parts 14 and 15 of the said lever. Said tight- 80 ening-lever is operated to tighten said wires by forcing it down thereagainst as far as possible by hand, and then by the operation of the nut or sleeve 16 said lever is moved with great power to apply such strain to the wires 85 A as may be required. By a similar bracket and tightening device at the opposite end of the track sufficient strain is put on the wire tracks to afford a suitable support for the upper end of a ladder 17, provided with a truck 90 or trolley 18. Said trolley is of the usual construction, except that guards 19 are provided, which are adjustable on the frame of the truck toward and from the under side of the wheels of said truck and which guards are set in close 95 proximity to the under side of the said wheels when they are in engagement with the wire and whereby they are prevented from disengagement therewith should the ladder to which the truck is secured receive a sudden 100 shock. Said guards 19 consist of a stud (see Fig. 5) having a screw-threaded end projecting through a slot 20 in the side of the truck-frame, said slot being located in vertical po-

sition under the center of the truck-wheel. A nut on said threaded end of the stud serves to secure it in said frame in its proper place.

Fig. 4 shows a construction of bracket B, adapted to a single-wire track, and in said figure is also shown a modified construction of the tightening-lever, which, instead of being in two parts 14 and 15, as described, is made of one piece 21 and has a screw-threaded 10 end which engages with the head of a stud 22, pivotally secured near the free end of said arm 7, said connection permitting the lever 21 to assume any required inclined position relative to the base of the bracket. A nut 15 23 on said lever 21 bears against the head of said stud 22 and forcibly moves, when operated, the arm 7, as desired. When said desired position has been attained, a nut 24 on the stud 22 is tightened, thus securing said 20 stud. Fig 4^a shows the above construction in detail.

If the length of a track to be established requires it, one or more supports intermediate of the end brackets may be used to maintain 25 said tracks A in a horizontal position. Said supports are designated by 25, and one of them is shown in Fig. 1 in perspective and in plan view in Fig. 3, and consists of a base a and depending rod b, on the lower extrem- 30 ity of which the two arms d d are cast on a suitable hub d', which revolves freely in a horizontal plane on said rod b, being retained in position by the collars f, as shown. In Fig. 3 is also shown the disposition of the 35 arms d of the support relative to the track-wires.

As the ladder is moved in the direction of the arrow the truck strikes the arm d, extending across under the track, and swings it on its support, the second arm following 40 behind the said truck and engaging the under side of the track before the first of said arms has been swung free therefrom. The dotted position of the arms of said swinging support shows them in position to be engaged 45 by the return of the ladder and swing back to the position shown in full lines. By means of this construction the track may be supported in as many places along the line as may be necessary and the passage of the 50 truck on the ladder not be interfered with.

Having thus described my invention, what I claim, and desire to secure by Letters Patent, is—

A store-service trolley-track comprising one 55 or more wire tracks, anchor-brackets for each end of said tracks, a ladder and trolley secured thereto for engagement with said tracks, and means applied between the said anchor-brackets for tightening said wires consisting 60 of the arm 7, pivoted by one end above said tracks, and the opposite end thereof engaging said tracks, and means for forcibly moving said arm from an inclined position relative to said tracks to a position more nearly 65 at right angles thereto, substantially as described.

STEPHEN J. BRENNAN.
